UNITED STATES PATENT OFFICE.

CHARLES LEWIS HENDERSON, OF WOODSTOCK, ONTARIO, CANADA.

WRENCH.

No. 868,858.

Specification of Letters Patent.

Patented Oct. 22, 1907.

Application filed December 5, 1906. Serial No. 346,476.

To all whom it may concern:

Be it known that I, CHARLES LEWIS HENDERSON, of the city of Woodstock, in the county of Oxford and Province of Ontario, Dominion of Canada, have invented certain new and useful Improvements in Wrenches; and I hereby declare that the following is a full, clear, and exact description of the same.

This invention relates to a wrench having a movable jaw which can be quickly adjusted to the stationary 10 jaw and automatically tightened against the work as the jaws are locked in their set position.

The invention further relates to the peculiar construction of the locking and tightening mechanism for the movable jaw, and to the means for multiplying 15 the power applied to hold the jaws in their set position.

For a full understanding of the invention reference is to be had to the following description and to the accompanying drawings in which,

Figure 1, is a perspective view of the wrench showing the external appearance of the parts. Fig. 2, is a 20 sectional view of the wrench showing the normal position of the parts. Fig. 3, is a similar view to Fig. 2, with the parts positioned to hold the movable jaw against the work. Fig. 4, is a detail view on a larger 25 scale than the preceding views of the locking and tightening mechanism for the movable jaw. Fig. 5, is a perspective sectional view of the articulating member. Fig. 6, is a detail view of the stationary jaw. Fig. 7, is a detail view of the movable jaw. Fig. 8, is a detail 30 view of the pivoted hand grip.

Like letters of reference refer to like parts throughout the specification and drawings.

Forming part of the wrench is a body bar *f* having at one end a fixed jaw *f'* and at the other end a hand 35 grip *q* and a resisting piece *l* at the junction of the hand grip *q* with the adjacent end of the body bar. Formed in the body bar *f* is a slideway *h* extending from the fixed jaw *f'* inwardly towards the resisting piece *l*. Contained in the slideway *h* is the shank *b* of the movable 40 jaw *a*. Formed in the shank *b* is an elongated slot *b'* and extending through the slot *b'* is a pin *b''* held by the walls of the body bar, and formed on the rear face of the shank *b* are detent teeth *c*. Formed through the rear wall of the body bar *f* is an aperture 45 *f''* through which the detent teeth *c* are accessible. Inclosing the rear and side walls of the body bar is the articulating member *e* fulcrumed to the body bar by the fulcrum pin *a''* at a place adjacent to the fixed jaw *f'*. The articulating member *e* extends from the 50 fulcrum pin *a''* to a place beyond the resisting piece *l*. Opposed to the aperture *f''* is a detent dog *d* having its face adjacent to the shank provided with a series of detent teeth *d'* to engage with the detent teeth *c*. Formed in the detent dog *d* is a socket *d''* and contained 55 in the socket *d''* is the ball *e'* of the pivoted arm *e''* fulcrumed to the articulating member *e* and

arranged to position the detent dog so that its detent teeth will engage with the detent teeth *c*.

Bearing against the detent dog *d* and the adjacent part of the articulating member *e* is a spring *z* to hold 60 the detent dog positioned to enable its detent teeth to engage with the detent teeth *c* during the actuation of the articulating member. Formed in the body bar *f* below the slideway *h* is a recess *h''* extending inwardly into the body bar from the rear wall thereof and contained in the recess *h''* is a guide pin *s*. The articulating member *e* is provided with a guide tube *s'* which telescopes on the pin *s* and coiled on the pin *s* and tube *s'* is a spring *s''* to normally press the articulating member away from the body bar to cause the disengagement 70 of the teeth of the detent dog with the detent teeth of the shank of the movable jaw. Fulcrumed to the free end of the articulating member *e* is a hand lever *m* the fulcrum pin *m'* of which passes through the hand lever in the vicinity of its toe *m''*. The toe *m''* 75 engages with the resisting face *l'* of the resisting piece *l* to cause the inward movement of the articulating member to bring the teeth of the detent dog into engagement with the detent teeth of the shank of the movable jaw. The resisting face *l'* of the resisting piece *l* is inclined rearwardly and outwardly from the body bar to facilitate the sliding movement of the lever toe *m''* thereon as the articulating member closes against the body bar.

The operation of the invention is as follows.—The 85 movable jaw *a* is extended while the parts are in the position shown in Fig. 1, to enable the jaws to straddle the work. The movable jaw is then closed while the parts are in the same position until both jaws are in contact with the work. The hand lever *m* is then 90 pressed towards the hand grip *q* and this movement of the hand lever causes the articulating member *e* to swing in an arc towards the body bar *f* and bring the detent teeth of the detent dog into engagement with the detent teeth of the shank. As the articulating 95 member swings towards the body bar the first tooth *l''* of the detent dog, engages with the aligned detent tooth *c* of the shank and as the articulating member continues its movement the pivoted arm *e''* brings the remaining teeth of the detent dog into engagement with the aligned detent teeth of the shank. All the detent teeth of the detent dog are then in engagement with a corresponding number of the detent teeth of the shank, and the continued movement of the articulating member carries the detent dog in a curvilinear plane and 100 thus presses the shank towards the inner end of the slideway to intensify the bite of the jaws on the work. When the pressure on the hand lever is released the articulating member returns to its normal position under the influence of the spring *s''* and releases the 105 shank of the movable jaw from engagement with the teeth of the detent dog. When the articulating mem-

ber is in this position the movable jaw is free to move outwards or inwards. The outward movement of the movable jaw is limited by the pin b'' engaging with the end of the slot b' and the outward movement of the articulating member is limited by the engagement of the toe of the hand lever m with a stop o at the outer end of the resisting piece l .

The holding power exerted on the detent dog is equal to the combined length of the articulating member and hand lever multiplied by the applied power divided by the distance of the detent dog from the fulcrum, and this holding power is intensified by the engagement of the hand lever with the resisting face of the resisting piece.

Having thus fully described my invention, what I claim as new, and desire to secure by Letters Patent is:

1. A wrench comprising a body bar having a slideway lengthwise therein, with an aperture in one of its walls communicating with the slideway, a stationary jaw at one end of the body bar, a hand grip at the opposite end, a resisting piece at the junction of the hand grip and body bar having a smooth inclined surface, a movable jaw, a shank for the movable jaw movable lengthwise in the slideway, detent teeth for the shank, an articulating member fulcrumed to the body bar, a detent dog carried by the articulating member and movable through the aperture in the body bar having detent teeth to engage with the detent teeth of the shank, and a hand lever fulcrumed to the free end of the articulating member, and slidably engaging with the inclined surface of the resisting piece.

2. A wrench comprising a body bar having a slideway lengthwise therein, with an aperture in one of its walls communicating with the slideway, a stationary jaw at one end of the body bar, a hand grip at the opposite end a resisting piece at the junction of the hand grip and body bar having a smooth inclined surface, a movable jaw, a shank for the movable jaw movable lengthwise in the slideway, detent teeth for the shank, an articulating member fulcrumed to the body bar, a detent dog having a series of detent teeth to engage with the detent teeth of the shank, an arm pivoted to the articulating member, and to the detent dog, a spring engaging the detent dog, and the articulating member to hold the detent dog positioned to engage with the detent teeth of the shank, a spring to restore the articulating member and detent dog to their normal position when relieved of the actuating power, and a lever fulcrumed to the articulating member and slidably engaging with the inclined surface of the resisting piece.

a series of detent teeth to engage with the detent teeth of the shank, an arm pivoted to the articulating member, and to the detent dog, and a hand lever fulcrumed to the free end of the articulating member slidably engaging with the inclined surface of the resisting piece.

45

3. A wrench comprising a body bar, having a slideway lengthwise therein, with an aperture in one of its walls communicating with the slideway, a stationary jaw at one end of the body bar, a hand grip at the opposite end, a resisting piece at the junction of the hand grip and body bar having a smooth inclined surface, a movable jaw a shank for the movable jaw, movable lengthwise in the slideway, detent teeth for the shank, an articulating member fulcrumed to the body bar, a detent dog, an arm pivotally connecting the detent dog with the articulating member, a spring to restore the articulating member and detent dog to their normal position when relieved of the actuating power, and a hand lever fulcrumed to the free end of the articulating member slidably engaging with the inclined surface of the resisting piece.

50

4. A wrench comprising a body bar, having a slideway lengthwise therein, with an aperture in one of its walls communicating with the slideway, a stationary jaw at one end of the body bar, a hand grip at the opposite end, a resisting piece at the junction of the hand grip and body bar having an inclined surface, a movable jaw, a shank for the movable jaw movable lengthwise in the slideway, detent teeth for the shank, an articulating member fulcrumed to the body bar, a detent dog having a series of detent teeth to engage with the detent teeth of the shank, an arm pivoted to the articulating member, and to the detent dog, a spring engaging the detent dog, and the articulating member to hold the detent dog positioned to engage with the detent teeth of the shank, a spring to restore the articulating member and detent dog to their normal position when relieved of the actuating power, and a lever fulcrumed to the articulating member and slidably engaging with the inclined surface of the resisting piece.
